(57) **CLAIM**

The ornamental design for a curved pyramid drying ball with round nodules and patch, as shown and described.

DESCRIPTION

FIG. 1 is a top perspective view of the curved pyramid drying ball with round nodules and patch;

FIG. 2 is a bottom view thereof;

FIG. 3 is a top view thereof;

FIG. 4 is a rear view thereof;

FIG. 5 is a side view thereof;

FIG. 6 is second side view thereof; and,

FIG. 7 is a top perspective view of FIG. 1 in which a portion of two side faces are visible.
